FOREIGN PATENT DOCUMENTS

WO 2008094566 8/2008

Primary Examiner — Doris Clark*(74) Attorney, Agent, or Firm* — Wegman, Hessler & Vanderburg(57) **CLAIM**

I claim the ornamental design for a cross spline for a wall panel system, as shown and described.

DESCRIPTION

FIG. 1 is a top perspective view of a cross spline for a wall panel system of the present invention;

FIG. 2 is first side view thereof;

FIG. 3 is a second side view thereof;

FIG. 4 is a top view thereof;

FIG. 5 is a bottom view thereof;

FIG. 6 is a front view thereof; and,

FIG. 7 is a rear view thereof.

The ornamental design which is claimed is shown in solid lines in the drawings. Any broken lines in the drawings are for illustrative purposes only and form no part of the claimed design.

1 Claim, 3 Drawing Sheets---
